US0D1073536S

(12) **United States Design Patent** (10) Patent No.: **US D1,073,536 S**
(45) Date of Patent: ** May 6, 2025

(54) **CAB**

(71) Applicants: **JiangSu XCMG Construction Machinery Research Institute LTD., Jiangsu (CN); Xuzhou XCMG Port Machinery Co., Ltd., Jiangsu (CN)**

(72) Inventors: **Liwei Xiao, Jiangsu (CN); Yilin Lu, Jiangsu (CN); Geng Xue, Jiangsu (CN); Haijun Zhang, Jiangsu (CN)**

(73) Assignees: **JiangSu XCMG Construction Machinery Research Institute LTD., Jiangsu (CN); Xuzhou XCMG Port Machinery Co., Ltd., Jiangsu (CN)**

(**) Term: **15 Years**

(21) Appl. No.: **29/892,431**

(22) Filed: **May 18, 2023**

(30) **Foreign Application Priority Data**

Feb. 13, 2023 (CN) 202330045459.3

CLAIM

The ornamental design for a cab as shown and described.

DESCRIPTION

FIG. 1 is a first perspective view of a cab showing our new design;

FIG. 2 is a second perspective view thereof;

FIG. 3 is a third perspective view thereof;

FIG. 4 is a fourth perspective view thereof;

FIG. 5 is a front view thereof;

FIG. 6 is a rear view thereof;

FIG. 7 is a left side view thereof;

FIG. 8 is a right side view thereof; and,

FIG. 9 is a top view thereof.

1 Claim, 9 Drawing Sheets
